UNITED STATES PATENT OFFICE.

HENRY H. DOERING, OF CHICAGO, ILLINOIS.

PRINT MACHINE.

Application filed August 15, 1921. Serial No. 492,252.

To all whom it may concern:

Be it known that I, HENRY H. DOERING, a citizen of the United States, and a resident of Chicago, in the county of Cook and State 5 of Illinois, have invented certain new and useful Improvements in Print Machines, of which the following is a description, reference being had to the accompanying drawings, which form a part of my specification.

My invention relates to a machine more especially intended for forming and producing butter prints; the invention having for its object the provision of a construction 15 whereby the formed butter or prints will be of uniform density or compactness and therefore of uniform weight.

One object of my invention is to provide a machine whereby the texture and consistency of the butter will be improved and 20 the machine arranged to suit atmospheric conditions or temperatures and therefore to suit the condition or consistency of the butter which is being forced through the machine; that is to say, the invention contemplates, among other things, means whereby the pressure on the butter may be increased or diminished in accordance with its 25 hardness or softness, so that uniform strips or ribbons of butter may be discharged through the discharge orifice or throat of the moulding-head so that the prints resulting from the cutting or print-forming means will be of uniform weight.

Another object of my invention is to provide means whereby the moulded butter will be so acted on in its passage through the machine as to cause a sealing of the pores to prevent "bleeding" and therefore to overcome the production of what is known as 35 "leaky" butter.

A further object of my invention is to provide means whereby the discharged ribbon of butter will be uniformly cut into prints 40 of the desired size; the movable portion of the cutting mechanism being made to travel or operate at a speed commensurate with the speed of discharge from the moulding-head of the machine.

The above enumerated objects as well as the advantages of my invention will all be more readily comprehended from the detailed description of the drawings where- 45 in:

Figure 1 is a top plan view of my im-

proved machine, with the driving mechanism broken away and a portion of the wrapping table shown.

Figure 2 is a side elevation of the construction as disclosed in Figure 1.

Figure 3 is a longitudinal sectional view taken on the line 3—3 of Figure 1 looking in the direction of the arrows.

Figure 4 is a vertical sectional view taken on the line 4—4 of Figure 2 looking in the direction of the arrows.

Figure 5 is a vertical sectional view taken on the line 5—5 of Figure 2 looking in the direction of the arrows.

Figure 6 is a cross sectional view taken on the line 6—6 of Figure 4 looking in the direction of the arrows.

Figure 7 is an enlarged detail sectional view of the discharge end of the main portion of the machine.

Figure 8 is a detail view in perspective of the pressure regulating means, and

Figure 9 is a detail view in perspective of the discharge end or throat controlling member.

The invention, as exemplified in the drawings, comprises a suitable supporting table or platform 15 on which is mounted a frame or housing 16 provided with semi-circular channels or grooves in the bottom thereof, as shown in Figure 8 at 17; the channels or grooves being disposed lengthwise of the housing 16 and partially separated by means of the vertically disposed rib 18 extending longitudinally of the housing 16. The housing 16 at one end thereof is closed to provide suitable bearings as at 19 for the rotatably mounted worms 20, 20, which are arranged parallel in the bottom of the semi-circular grooves or channels 17, 17 and extend from end to end of the housing 16.

The worms 20, 20 are intended to be rotated toward each other by driving mechanism, not shown, which may be of any suitable construction. The housing 16 is provided with a top 21 which in turn is provided with a longitudinal opening therein disposed lengthwise of the worms and more generally in alignment with the portion intermediate of the worms 20, 20 as more clearly shown in Figure 1. The opening in the top is surrounded by a vertically disposed frame or portion 22 formed integral with or otherwise secured to the main portion of the top 21, thus providing a suitable wall about the

opening through which the material or butter is to be fed. The opening enclosure or wall 21 is shown provided with a plurality of removable pressure plates or members 23, 24, 25 and 26 whose lower sides are cut away in semi-circular manner to fit the contour of the worms 20, 20 and therefore to conform with the semi-circular grooves 17, 17 in the bottom of the housing, so that the forward 10 end of the housing will be provided with a pair of cylindrical passages, communicating with each other by the narrow longitudinal opening between the vertically disposed rib 18 in the bottom of the housing 16 and the 15 downwardly disposed portion or rib 27 formed on the bottoms of the top 21 and the removable plates or members 23, 24, 25 and 26; the rib on the bottom of the innermost plate or member 26, as well as the 20 semi-circular grooves, being preferably cut away or flared to the outer side of the plate or member in the upwardly disposed direction shown at 28 in Figures 7 and 8. In thus forming the plate 26 as described, a 25 flared end to the cylindrical passages is provided which will ensure the self-feeding of the material or butter through the housing when the worms 20, 20 are revolved. In order that the members or plates 23, 24, 25 30 and 26 may be properly positioned in the frame 22, I provide the frame on the interior thereof with a shoulder 29 on each longitudinal side thereof, while the plates or members 23, 24, 25 and 26 are kerfed as at 35 30 in Figure 8 to receive the shoulder 29 and thereby maintain the plates in proper spaced relation with the bottom of the frame or housing 16.

The plates or members 23, 24, 25 and 26, 40 as well as the end wall 22 of the opening enclosure wall or frame of the top, are all apertured for the passage of a suitable bolt or fastening member 31 held in place in any suitable manner, as for example by means 45 of the butterfly nut 32, see Figures 7 and 8, and in order that there may be no protrusions on the outer face of the innermost plate 26, the latter is provided with a countersunk portion about the aperture to 50 receive the head of the bolt 31. As the worms 20, 20 are intended to be in intimate relation with the bottom of the housing 16 as well as the sides and top, they therefore need not be journaled at the inner ends. 55 The plates or members 23, 24, 25 and 26 will cause the butter or material fed through the machine to be subjected to pressure which must be consistent with the condition of the butter, namely whether in a hard or a soft 60 condition, in order that the compactness of the butter may be controlled and the discharged ribbon and resultant prints thereby all caused to be of substantially uniform weight. For this reason the members 23 to 65 26, inclusive, are made removable so that

the pressure on the butter may be controlled or regulated; that is to say when the butter is in more or less soft condition, the number of plates or members is reduced so as to lessen the resistance to or pressure on the butter, while on the other hand if the butter is in a hard state, the number of plates or members are increased in order that the greater pressure will be applied to the butter before it enters the moulding head or discharge throat of the machine. 70 75

The forward end of the housing or frame 16 adjacent the discharge ends of the worm is provided with a moulding head 33 which is preferably shown made of suitable metal 80 having a converging throat 34; the head being bolted or otherwise suitably secured to the housing or frame 16. In order that a proper uniform sized opening may be obtained so as to produce uniform strips or 85 ribbons of butter, the throat portion of the moulding head is provided with a block 35 adapted to move transversely of the throat, which is slotted in one side as shown at 36 in Figure 4 to permit the reduced end 35^a of the block 35 to extend therethrough. In order that the block 35 may be adjusted to the proper position, the throat portion 34 of the moulding head is provided with a pivoted yoke or strap 37, see Figures 4 and 95 6; the central portion of the yoke or strap being provided with an apertured enlargement or boss 38 internally threaded to receive the adjusting bolt or screw 39. The inner end of the bolt or screw is provided with a flange or washer 40 which is adapted to ride in a slot 41 formed in the end of the block 35. With the construction just described, it is apparent that the block 35 may be moved transversely of the throat in 105 the direction desired by proper rotation of the screw or bolt 39. To ensure proper positioning of the block 35, I prefer to provide the same, on the top and bottom surfaces thereof, with similar slots 42, see 110 Figure 9, adapted to receive the heads of bolts 43 which latter may also constitute the pivotal points for the yoke 37; a clamping relation being provided by means of butterfly or other suitable nuts as shown at 115 44 in Figure 4.

The three side walls of the moulding head 33, namely the sides other than that provided with the slot 36 for the reduced end of the block 35, are chambered to provide a water-receiving chamber as shown at 45 in Figures 2 and 7 and the moulding head is provided with a valved inlet-conduit 46 and a valved outlet-conduit 47 which communicate with the chamber 45 for admitting and withdrawing the water therefrom. The object of this chamber is to enable the moulding-head to be heated to a sufficient degree by means of proper tempered or heated water which may be ad- 120 125 130 135 140 145 150 155 160 165 170 175 180

mitted from a suitable source of supply by the conduit 46 and circulation through the head permitted by opening the valved conduit 47. It has been found in practice that 5 by increasing the temperature of the moulding-head to a certain degree, will cause the butter passing through the moulding-head to have its outer surface so affected or acted upon as to seal the pores and thereby prevent 10 the moisture within the cells of the butter from readily oozing out; that is to say, by properly tempering the moulding-head, a smooth outer surface is provided on the moulded butter which will prevent 15 "bleeding", so that with my improved construction the production of what is known as "leaky" butter will be prevented.

Operatively disposed beyond the discharge throat of the moulding-head and 20 mounted on the supporting table or standard 15 are a suitable number of rotatably mounted rollers 48 disposed transversely of the frame and suitably journaled therein by means of the bearing-blocks 49. These 25 rollers are intended to receive an endless belt 50 which is provided with a plurality of metallic prongs or fingers 51 arranged in pairs, as shown in Figures 2, 3 and 5, and in alignment at opposite edges of the 30 endless element or belt 50. The different pairs of prongs or fingers 51 are arranged in predetermined spaced relation along both edges of the belt 50, while the spacing intermediate of the fingers of each pair, or the 35 slots in each prong, are adapted to successively receive the wires 52 secured to the rims of the wheels 53, 53. The wheels 53 are identical in construction and mounted beyond opposite sides of the endless element 40 or belt on a journal 54 supported by a suitable frame or standard 55 secured to opposite sides of the table or supporting frame 15. The rims of the wheels 53 are shown slotted or apertured at predetermined 45 points, corresponding with the spaced relation between the different pairs of fingers or prongs 51, to receive the wires 52 which are held in taut condition by any suitable mechanism as for example the 50 butterfly-nuts 56 threaded on the ends of the wires.

The moulding-block 35 with the throat of the moulding head is adapted to compress or mould the butter into strips or 55 ribbons, rectangular in cross-section and of prearranged density or compactness and the cutting wires 52 with the fingers or prongs are so correlated that the moulded strip or ribbon of butter will be cut into 60 lengths constituting pound prints. With the cutting mechanism, comprising the endless element or belt and the wire-holding wheels, mounted to freely rotate, it is evident that movement of the endless belt will 65 be induced by the action of the ribbon or

strip of butter issuing from the moulding-head; and as the wheels 53 are of predetermined size, at least one of the cutting wires will at all times be in engagement with or intermediate of a pair of prongs, so that 70 movement of the belt 50 will necessarily cause rotation of the wheels 53 and therefore induce the respective cutting wires 52 to successively come into cutting contact with the traveling ribbon or strip of butter. 75 With this construction, it is apparent that the cutting mechanism will at all times operate at a speed commensurate with the speed at which the butter is moulded by and discharged from the moulding-head. 80

As it is frequently desired to provide butter prints of half pound or quarter pound sizes, I have devised an auxiliary cutting mechanism which is adapted to be removably secured to the throat of the moulding-head 33 and in the particular exemplification this auxiliary mechanism comprises a frame portion 57 adapted to fit onto the throat or discharge end of the moulding-head and is secured in place by means of the 90 bolts 43 with the clamping or butterfly nuts 44 which secure the yokes 37 in place and also constitute guides for the moulding-block 35, see Figures 3, 4 and 7. The frame member 57 is internally formed to constitute 95 a continuation of the throat of the moulding-head and is shown provided with a ledge or supporting plate 58 formed integral therewith or suitably secured thereto so as to provide means whereby the discharging butter may be properly conveyed onto the endless element or belt 50. The frame member 57 is shown provided with a pair of cutting wires or members 59 and 60 arranged at right angles to each other so as to 100 intersect at the center of the throat opening of the moulding-head. The wires are held taut in any suitable manner, as for example by the threaded plugs or bolts and nuts as shown at 61; the wire 59 being disposed vertically while the wire 60 is arranged horizontally; the two wires causing the throat opening to be divided into quarter portions as very clearly shown in Figure 4, thereby 105 causing the butter issuing from the throat 110 of the moulding-head to be cut into quarter sections so that when the quartered strip or ribbon is subjected to the action of the final cutting mechanism, to-wit the wires 52, the quartered sections will be cut into 115 quarter-pound prints. If it is desired to produce half-pound prints, it is apparent that the vertically disposed wire 59, or the wire 60, may then be removed by simply unscrewing the nuts and the threaded plugs which 120 hold the wire, so that the strip or ribbon of butter will then be halved, with the result that when finally subjected to the cutting wires 52, half-pound prints of butter will be 125 provided.

The prints will be delivered by the endless element or belt 50 onto a receiving and wrapping table, a portion of which is shown at 62 in Figures 1 and 2, where the butter may be wrapped in paraffine or other suitable paper and then placed in suitable cartons in the usual manner.

My improved machine as heretofore described and as illustrated in the drawings, 10 is adapted to properly work and mould butter of varying consistencies or conditions, that is to say the machine is adapted to properly work and mould butter whether in a more or less soft state or in a frozen or 15 hard state; it being essential in machines of this type to provide a construction whereby the butter will be properly and sufficiently worked to improve the texture and consistency thereof. This can readily be accomplished by lengthening or shortening the 20 worm enclosing portion of the machine, namely the portion where the butter is subjected to working pressure; it having been found in practice that the working pressure 25 must be increased in proportion to the hardness of the butter and for that reason the number of plates are increased according to the degree of hardness. On the other hand, the number of plates must be decreased in 30 proportion to the softness of the butter so as to shorten the working portion of the machine and therefore to lessen the working pressure or resistance to the butter. In the drawings and more particularly in Figure 35 8, the end wall 22 of the top of the housing 16 is numbered 1 and each succeeding plate viewed from the right hand is numbered 40 consecutively in order that the proper positioning of the plates 23, 24, 25 and 26 may be ensured. Where the butter is in a soft condition, the intermediate plates 23, 24 and 45 25 numbered 2, 3 and 4, respectively, may be removed and plate 26, which is numbered 5, brought into juxtaposition with the end wall numbered 1, of the top plate of the 50 housing; it being advisable to employ plate 26 and numbered 5 because of the flared and gradual opening to the circumferential grooves produced thereby. It is also apparent that the temperature of the heating water passed through the chamber 45 of the moulding-head 33 may be varied in accordance with general atmospheric conditions and the condition of the butter.

55 I have illustrated what I believe to be the best embodiment of my invention, having described the same in terms employed as terms of description and not as terms of limitation, as structural modifications are 60 possible and may be made without, however, departing from the spirit of my invention.

What I claim is:—

1. A machine of the character described, comprising a butter-receiving housing having screw-worm receiving grooves and a

butter-introducing opening in the top, the top wall of the housing being formed in vertically disposed sections, the bottoms whereof have surfaces conforming with the grooves in the bottom of the housing to 70 subject the butter passing therethrough to pressure, said sections being removably secured in place in order that the length of the pressure-applying portions of the housing may be regulated, means whereby said sections may be held in place against movement, a chambered moulding head secured to the delivery end of said housing, and means whereby a heating medium may be circulated through the chamber of said 80 head.

2. A machine of the character described, comprising a butter working housing provided with a pair of parallelly disposed worm screws, an opening in said housing 85 above said screws for the introduction of the butter, a plurality of vertically disposed sections or plates removably secured in the top opening and provided with concaved bottoms to extend about the tops of the 90 worm screws, said plates being adapted to regulate the length of the worm-enclosing portion or housing and control the pressure applied to the butter, means whereby said sections or plates are removably secured in 95 place, a moulding head provided with an open side, and a throat member slidably mounted in said head to constitute a laterally adjustable throat whereby to form and determine the size of the mass of butter delivered therethrough.

3. A machine of the character described, comprising a butter-receiving casing having an opening in its top, a pair of parallel worm-receiving grooves in the bottom, 105 worm-screws disposed lengthwise in said grooves and in slight spaced relation, with the space between the screws disposed immediately beneath the opening in the top, a plurality of vertically disposed removable sections or plates mounted in said opening and provided with dished bottoms conforming with the contour of the worms and constituting the top wall of the worm-grooves 110 whereby to regulate the pressure on the butter, a moulding head secured to the delivery end of the casing, said moulding head being provided with a water chamber in its walls, and means whereby circulation of hot water through said chamber may be 115 controlled.

4. A machine of the character described, comprising a water-receiving housing having a removable top provided with an opening disposed lengthwise thereof, a pair of 125 worm-screws rotatably mounted lengthwise of the casing and in slight spaced relation, with the space intermediate of the worms disposed centrally beneath the opening in the top, a plurality of removable inter- 130

changeable vertically disposed sections secured in said opening and provided with dished bottoms conforming with the contour of the worms, said sections constituting the top wall of the butter-working portion of the casing and adapted to control pressure on the butter, a moulding head secured at the delivery end of the casing and provided with an open side, a laterally slideable block passing through said open side to provide an adjustable throat whereby to determine the size and form of the butter issuing from the moulding head, a regulating screw-carrying frame disposed about the end of said block, and means removably secured to the moulding head whereby the moulded butter may be cut into a pre selected number of sections, in combination with means whereby the delivered butter may be automatically cut into predetermined lengths.

5. In a machine of the character described, a moulding head provided with an open side, a block slideable through said open side to provide an adjustable outlet controlling member, a yoke pivotally secured to the moulding head and disposed about the end of said block and having controlling relation therewith, a frame removably secured to the outlet end of said moulding head and provided with removable cutting wire-holding means adjustably mounted therein.

6. In a machine of the character described, a moulding head provided with a regulable outlet, the walls of the head being chambered and arranged to have hot water circulate therethrough, one side of the outlet end of the head being open, a yoke pivotally secured to the head and disposed transversely, a slotted block slideable transversely of the outlet, means carried by the yoke, having controlling relation with the block whereby the latter may be moved laterally of the head, guide means in the head adapted to extend into the slots of the block, a frame removably secured to the moulding head and disposed forward of the outlet of said head, said frame being provided with cutting wires arranged in predetermined relation and disposed across the outlet opening of the moulding head, and means adjustably mounted in said frame for removably securing the cutting wires in place and maintaining them in taut condition.

7. In a machine of the character described, a butter-working casing provided with a top having a longitudinal opening therein and a worm-receiving channel in the bottom of the casing, a plurality of pressure-inducing plates disposed vertically in said opening, with the bottom edge of each plate being dished to constitute the top wall of the worm-receiving channel so as to regulate the length of the working pressure portion of

the casing, and means whereby any one or all of the plates may be removably secured in place.

8. A machine of the character described, comprising a butter working portion provided with a moulding-head whereby the butter is formed into strips or ribbons of predetermined compactness and rectangular in cross section, in combination with cutting mechanism disposed beyond the discharge end of said moulding-head, said cutting mechanism comprising rotatably mounted means provided with a plurality of cutting wires disposed transversely, and an endless element provided with a plurality of prongs or fingers arranged at predetermined distances apart commensurate with the distance intermediate of the cutting wires of said mechanism, said prongs or fingers being adapted to engage with said rotatably mounted means whereby the latter is caused to rotate when said endless element is actuated through the movement of the ribbon or strip of butter issuing from the moulding-head.

9. In a machine of the character described, cutting mechanism comprising rotatably mounted means provided with cutting elements arranged at predetermined distances apart circumferentially about said means, and an endless element arranged to travel in a plane beneath said rotatably mounted means, said endless element being provided with a plurality of prongs or fingers arranged in predetermined spaced relation commensurate with the spacing intermediate of the cutting elements of said rotatably mounted means.

10. In a machine of the character described, cutting mechanism comprising a pair of concentrically mounted wheels arranged in spaced relation, cutting wires adjustably secured in predetermined spaced relation on the peripheries of said wheels, an endless element adapted to travel in a horizontal plane adjacent to the orbit of the wheels, said element being provided with projections disposed at an angle thereto and arranged at predetermined distances apart commensurate with the distance between said cutting wires so as to successively engage each succeeding wire whereby rotation of the wheels with the cutting wires is induced by the travel of said endless element.

11. A machine of the character described, comprising a butter working portion provided with a moulding-head and a delivery ledge or plate, in combination with an endless element mounted in juxtaposition to said delivery ledge or plate, said endless element being provided with a plurality of vertically disposed projections arranged in predetermined spaced relation, said endless element being adapted to be actuated by the movement of the butter issuing from said

moulding-head, and cutting wire holding means rotatably mounted above said endless element, said cutting wire holding means being adapted to be actuated by the projections on said endless element.

12. In a machine of the character described, a butter-working portion comprising a casing provided with a pair of rotatably mounted worms disposed lengthwise thereof, said casing being provided with removable sections disposed above said worms and provided with a pair of dished surfaces or grooves conforming with the contour of the worms to provide adjustable closed channels whereby the working pressure portion of the casing may be regulated, and a moulding head secured at the delivery end of said casing, said moulding head including means whereby the temperature of the moulding head may be increased.

13. A machine of the character described, comprising a butter working casing having a receiving opening in the top, revolvably

mounted worms in the casing, removable sections or plates whereby the worm enclosing portion of the section may be regulated, a water chambered moulding-head removably secured to the delivery end of said casing, an orifice controlling block slidably mounted in said head, means whereby said block may be held in adjusted position, an automatically controlled cutting mechanism disposed beyond said cutting head, said cutting mechanism comprising an endless element adapted to receive the delivered butter and to be actuated thereby, and means rotatably mounted above the endless element for cutting the strip of butter on the endless element into prints of predetermined size, said last mentioned rotatably mounted means being adapted to be actuated by the endless element.
